UNITED STATES PATENT OFFICE.

FRANK X. HILL, OF KEYPORT, NEW JERSEY.

HOSPITAL BED.

Application filed February 8, 1922. Serial No. 534,945.

To all whom it may concern:

Be it known that I, FRANK X. HILL, a citizen of the United States, residing at Keyport, in the county of Monmouth and State of New Jersey, have invented certain new and useful Improvements in Hospital Beds, of which the following is a specification.

This invention relates to hospital beds and more particularly to a novel and improved bed appliance or attachment whereby a patient may assist himself and attend to the natural functions of the body when incapacitated and lying in bed.

The primary object of the invention is the construction and provision of a hospital bed appliance which dispenses with the bed pan and the assistance of a nurse, said appliance having means whereby a container may be moved by the patient to receive the excrement and shifted to one end of the bed so that the container may be subsequently removed.

Another and very important object of the invention is the construction of a hospital bed appliance of the class above set forth which is capable of use and adapted to be installed on various types of beds, and one wherein the parts are extremely simple in construction, easily assembled, highly efficient in operation, practical and otherwise capable of being manufactured at an extremely low cost whereby its commercial possibilities are greatly enhanced.

I attain the above objects and others by the accompanying drawing showing a preferred form of the invention wherein;

Figure 1 is a side view partly in section showing my invention as applied to a conventional type of hospital bed.

Figure 2 is a front view.

Figure 3 is a view showing the spring, mattress and sheet or cover, and

Figure 4 is a perspective of a mattress protecting cover.

Figure 5 is a plan of the receptacle supporting structure.

Referring now to the drawings wherein like reference characters designate corresponding parts throughout the several views, 5 5 designates the head and 6 the foot of a conventional type of hospital bed having the usual side rails 7, 8 which support the wire spring 9 and mattress 10 as clearly disclosed by Figure 1 of the drawing.

55 A pair of parallel longitudinally extending, U-shaped channel bars or rods 11, 12 con-

nect the head and foot of the bed and form a trackway or guide for the rollers 13 which support the receptacle or container, which may be shaped similar to a bed pan. The 60 receptacle or container supporting structure comprises a transverse, inverted U-shaped bar 14 having a front ledge 15 on which the pan 16 rests, attaching ears 17 having the rollers 13 at their upper ends permitting 65 the pan supporting structure to be easily moved. The bowed front 18 of the pan supporting structure has connected thereto a rearwardly extending framework 19 having 70 braces 20; the rear of said framework 70 being provided with a vertical portion 21, the upper curved end 22 being connected to a sliding bar 23 and disposed so as to lie adjacent the spring and mattress. The cross connecting bar 14 is preferably provided 75 with vertical actuating handles or arms 25 with hand grips 25^a on each side of the bed proper so that the patient may move the entire receptacle supporting structure from a position substantially centrally of the bed to 80 the end or foot of the bed for the obvious purpose.

As shown, the bed is provided with a specially designed spring and mattress, the former having a hinged central closure 26 85 and the mattress also having a central hinged portion 27, which together with the closure 26 is normally supported by the upper curved end 22 as shown.

As the receptacle supporting structure is 90 moved toward the head of the bed it will be readily seen that the hinged portion of the mattress and hinged closure will fall to the dotted line position and lie open. As the handles are urged forwardly the mattress 95 and spring are closed by the receptacle supporting structure and the receptacle may be moved to the foot of the bed where it may be removed. Referring to Figures 3 and 4 it will be seen that I have also provided a 100 mattress covering 28 for the hinged portion of said mattress, which covering may be removed and replaced when it is to be laundered.

It will be thus seen from the above construction that the receptacle supporting structure also performs the function of opening and closing the hinged portion of the mattress and spring and by the provision of suitable stops at the foot and front portion of the central guide rails, the patient may move the receptacle supporting struc-

ture to the desired position without the assistance of a nurse and thus the patient may attend to his own needs when incapacitated

5 In the accompanying drawings, I have illustrated my invention embodied in one form by way of example, and which construction has been found to answer to a satisfactory degree the results to be obtained.
10 It would be manifest, however, that other forms of embodiment may be adopted, and that the construction may be variously changed and modified by the skilled mechanic without departing from the limits
15 of the invention. Further it will be understood that the invention is not limited to any particular form of construction in the parts, except in so far as such limitations are specified in the subject matter being
20 claimed.

Having thus described my invention, what I claim as new, and desire to secure by United States Letters Patent is:—

1. A bed appliance of the class described
25 in combination with the foot and head sections, a pair of connecting rails between the foot and head sections, a receptacle supporting structure movable on the rails and be-

neath a hinged bed spring and mattress section, an element fixed on the supporting structure to open and close said section by 30
slidable engagement therewith, and means disposed on each side of the bed whereby a patient may slide said supporting structure to different positions.

2. A bed appliance of the class described in combination with the foot and head sections, a pair of parallel connecting rails between the foot and head sections constituting a guide, a receptacle supporting structure 40 having rollers operable within the rails and beneath a hinged bed spring and mattress section, an element fixed on the supporting structure to open and close said section by
45
slidable engagement therewith, and arms connected to the receptacle supporting structure whereby the same may be moved by a patient to different positions with respect to the bed and the mattress.

In testimony whereof I affix my signature 50
in presence of two witnesses.

FRANK X. HILL. [L.S.]
